SAW VISE

Leoni Carpentier, Montreal, Quebec, Canada

Application August 11, 1947, Serial No. 767,973

In Canada August 24, 1946

1 Claim. (Cl. 76—78)

1

The present invention pertains to a novel saw vise for securely holding a saw while it is being filed or set.

The principal object of the invention is to provide a simple and inexpensive device of this character and one that is effective in use. There is provided a fixed plate and a clamping plate movable relatively thereto. The movement of the clamping plate is secured from a shaft carrying an eccentrically mounted block which is fastened to the clamping plate through the fixed plate. Thus rotation of the shaft displaces the clamping plate relatively to the fixed plate.

Another object of the invention is to provide a simple dual structure of the character set forth. In this embodiment of the invention there is provided an angle bar representing the fixed plate and having a clamping plate slidably supported externally along each side thereof. As in the first construction, there is provided a shaft within the angle bar, and the shaft carries pairs of eccentrically mounted blocks. One block of each pair is attached to one of the clamping plates by rivets passing through the adjacent side of the angle bar, and the other block of each pair is similarly attached to the remaining clamping plate. The angle bar is preferably so positioned that the saw may be inserted vertically or horizontally, as desired, and the shaft is readily adjusted until the corresponding clamping plate is brought to clamping position.

The invention is fully disclosed by way of example in the following description and in the accompanying drawings in which:

Figure 1 is a perspective view of the device;

Figure 2 is an elevation at the open side;

Figure 3 is a section on the line 3—3 of Figure 2;

Figure 4 is a perspective of a modification; and

Figure 5 is a section on the line 5—5 of Figure 4.

Reference to these views will now be made by use of like characters which are employed to designate corresponding parts throughout.

In Figure 1 is shown a suitable table 1 on which the vise is supported by vertical legs 2 in a manner presently to be described. In the upper ends of the legs is rotatably mounted an operating shaft 3 carrying at one end a crank 4. The body of the vise comprises an angle bar 5 lying between the legs 2 and having one side vertical and the other upward and horizontal as shown in Figure 3.

The angle bar is held in a fixed position on the shaft by the means shown in Figure 1. This

means include a pair of angle irons 7 laid on a suitable base and spaced apart to form a channel. The inner or vertical sides of the members 7 are apertured at 8 and between them is mounted the lower end of a post 9 carrying bolts 10 that may be fastened adjustably in the apertures 8. A rod 11 has one end attached to one of the collars 21 to be described and its other end is fitted with a clamp 12 adjustable on the post 9. By adjustment of the post 9 along the members 7 and adjustment of the clamp 12 on the post, the angular position of the angle bar 5 is determined and fixed.

On each of the sides of the angle bar 5 is attached a clamping plate 13 along one edge by rivets 14, with spacers or washers 15 mounted on each rivet between the parts 5 and 13. Along its other edge, each plate 13 carried a row of bolts 16 passing slidably through the adjacent side of the angle bar 5, for a purpose that will presently be described.

The shaft 3 carries a number of eccentrics 17 mounted thereon in spaced relation and secured thereto. On each of these eccentrics is mounted a pair of blocks 18, 19, the former being attached to the bolts 16 of the vertical side of the angle bar 5, and the blocks 19 attached to the bolts 16 of the horizontal side of the angle bar. The bar 5 is further supported by angle brackets 20 attached thereto along its length and also fastened to collars 21 mounted on the shaft 3.

In the use of the device, the saw 22 to be filed is inserted beneath one or the other of the clamping plates 13, according to whether it is desired to lay the saw vertically or horizontally. The saw is inserted along the edge of the particular plate 13 that carries the bolts 16, as this is the yielding edge. The crank 4 is turned until the saw is clamped by the adjacent plate 13. It is evident that the mounting of the blocks 18, 19 permits either of the clamping plates 13 to be brought to clamping position.

In the modification shown in Figures 4 and 5, there is provided a channel body 25 and a clamping plate 26 along its lower surface. One edge of the clamping plate is attached loosely to the body by a series of bolts 27, with spacers 28 inserted between the plate and the body. The plate further carries rivets 29 passing slidably through the bottom of the body 25, for a purpose that will presently appear.

The edge of the plate opposite the spacers 29 is bent slightly at 30. Extending to one side of channel body 25 are fixed blades 32 adapted to

be driven into tree stumps or the like for supporting the device on the job.

A shaft 33 is suitably journaled lengthwise in the body 25 and carries a series of spaced eccentrics 34. On each eccentric is mounted a block 35 into which the rivets 29 are secured. Thus, as the crank 36 on the shaft 33 is swung, the blocks 35 will be raised or lowered and the clamping plate 26 moved with them. The saw 31 is clamped, obviously by drawing of the bent edge 10 38 of the plate 26 toward the bottom of the body 25.

Although specific embodiments of the inventions have been illustrated and described, it will be understood that various alterations in the details of construction may be made without departing from the scope of the invention as indicated by the appended claim.

What I claim as my invention is:

A saw vise comprising a fixed plate, a clamping plate laid along one side of said fixed plate 20

and movably supported thereon, a shaft along the other side of said fixed plate, an eccentric on said shaft, and a block on said eccentric and attached to said clamping plate through said fixed plate, said clamping plate having one edge attached loosely and spacedly to said fixed plate.

LÉONI CARPENTIER.
